UNITED STATES PATENT OFFICE.

CHARLES A. KEENE, OF SYRACUSE, NEW YORK.

RULING-MACHINE.

SPECIFICATION forming part of Letters Patent No. 759,719, dated May 10, 1904.

Application filed September 22, 1903. Serial No. 174,199. (No model.)

To all whom it may concern:

Be it known that I, CHARLES A. KEENE, a citizen of the United States, residing at Syracuse, in the county of Onondaga and State of 5 New York, have invented new and useful Improvements in Ruling-Machines, of which the following is a specification.

This invention relates to paper-ruling machines, and particularly to mechanism coöperating therewith for drying and stacking the ruled paper.

The invention contemplates the employment of simple mechanism for drying and stacking individual sheets or pieces of paper after passing through the class of machines set forth, said mechanism being of such structural arrangement as to render the same readily applicable to a ruling or other similar machine without affecting in the least the organization 15 of the essential elements of the latter. This mechanism is provided with adjustable features to accommodate paper of different sizes, and coöperating therewith is novel means for curving or dishing the paper to render its discharge positive with relation to the drying and 20 stacking mechanism.

The invention consists, primarily, in the use of a revoluble coil arranged at an angle adjacent to the delivery or discharge extremity of 30 a ruling or other similar machine and having means coöperating with opposite portions thereof to prevent the paper fed into the coil from turning with the latter.

The invention further consists in the use of 35 a revoluble coil having means adjacent thereto to engage opposite edges of the paper to prevent the latter from slipping out of place in the coil and also cause the same to be regularly and positively stacked.

40 The invention still further consists in the use of a revoluble coil having resisting means arranged adjacent to opposite portions thereof and at times wholly exterior of the coil, said means being adjustable to accommodate different sizes of paper fed to the coil and operating to hold the paper against loose movement between the members of the coil, but avoiding the least obstruction to the feed of the paper throughout the length of the coil 45 to a stack-support.

The invention still further consists in the specific construction and arrangement of parts, which will be more fully hereinafter set forth.

In the drawings, Figure 1 is a side elevation of a paper-ruling machine having my improved drying and stacking attachment connected thereto. Fig. 2 is a longitudinal section through the machine and showing the stacking-coil in elevation. Fig. 3 is a plan view of the attachment and showing the sheet 60 of paper carried thereby. Fig. 4 is a side elevation, partly broken away, of a modified form of coil. Fig. 5 is a section on the line 5 5, Fig. 4. Fig. 6 is a plan view of a modified form of attachment. Fig. 7 is a section on 65 the line 7 7, Fig. 6. Fig. 8 is an elevation of the paper-guide plates and the mechanism connected thereto.

Referring to the figures by numerals of reference, 1 is the frame of the machine, from 70 the front end of which extend standards 2, having brackets 3 at their upper ends, between which is arranged a roller 4. Standards 5 are also arranged on the bed of the frame at points adjacent the centers of the sides thereof, 75 and these standards also serve to support a roller 6 therebetween. A serving-table 7 is arranged at the front end of the frame 1 adjacent the standards 2. Shafts 8 and 9 are journaled upon the frame 1 in vertical alignment with each other and adjacent the standards 2, and upon each of these shafts is a drum 10, and the pass formed between the two drums is of sufficient width to permit the passage therethrough of a belt 11 and a series of 80 cords 12, together with a sheet of paper. The cords 12 are mounted on the rollers 4 and 6 and extend under the upper drum 10 and under a roller 13, arranged between the lower ends of the standards 5. The belt 11 is mounted on the lower drum 10 and upon a drum 14, arranged on a power-shaft 15, which is journaled in the frame 1 at a point under the standard 5. A crown 16 is secured within the upper portion of the frame 1 and between the 85 drums 10 and 14 and serves to hold the belt 11 in such position as to bring any paper thereon into contact with one or more ruling-pens 17, which are mounted on supporting 90 mechanism 18 of desired construction and ar- 100

rangement. That portion of the belt 11 located between the crown and the drum 10 is supported by a series of small rollers 19, which can be adjusted in any suitable manner, as by 5 means of screws 20. A gate 21 of the usual construction is mounted above the belt and between the pens and the drums 10 and is employed for regulating the supply of paper to the pens 17. A cam-wheel 22 is mounted on 10 a shaft 23, located under the crown 16, and has one or more cams 24 thereon, which is adapted to remove the pens from contact with the paper at desired intervals. Any suitable mechanism may be employed for producing 15 this result. The cam-wheel 22 and its shaft are preferably rotated by means of a gear 25, which meshes with an intermediate gear 26, adjustably connected to the frame 1 and adapted to receive motion from a gear 27, connected 20 to the shaft 15. A gear 28 is secured to the shaft 15, and drive-pulleys 29 are loosely mounted upon this shaft, but are adapted to be rigidly connected thereto by means of a clutch 30, operated in any suitable manner.

25 A sleeve 31 is loosely mounted on the shaft 15 and forms a bearing for shaft 32, to which is secured a gear 33, which meshes with the gear 28. A second gear 34 is feathered on the shaft 32 and meshes with a gear 35, secured to 30 a horizontal shaft 36. This shaft is mounted in a standard 37, arranged upon the frame 1 near its rear end, and the shaft 32 is revolvably mounted in a sleeve 38, swiveled or otherwise suitably connected to the center of the gear 35. The standard 37 is arranged upon a cross-strip 39, which is adjustably mounted on the frame 1 and is adapted to be secured, by means of bolts 40, in any position to which it may be adjusted. This cross-strip is preferably 40 arched, as shown, to extend over a coil 41, having its upper end bent inward to form an arm 42, provided with a vertical extension 43, which is in alinement with the longitudinal center of the coil. This coil is arranged at an angle to 45 the discharge extremity of the machine and in the present instance is disposed vertically. The extension 43 is journaled within the center of the cross-strip 39 and is supported thereby, and secured to the extension is a gear 44, which 50 meshes with a gear 45, secured to the shaft 36. Base-plates 46, having longitudinally-extending slots 37, are secured to a platform 48, arranged upon the bottom of the frame 1, and these base-plates have parallel vertical guide-strips 49 integral therewith and adapted to be 55 adjusted from or toward the sides of the coil. Guide-strips of this character are arranged adjacent to opposite portions and in rear of the exterior of the coil and are adapted to be adjusted from or toward each other so as to receive therebetween sheets of paper of different sizes.

60 Journalized within the frame 1, between the drum 14 and the coil 41, is a vertically-adjustable roller 50, which is adapted to be rotated by

means of a cord or belt 51, mounted upon said roller and the drum 14. Secured in the frame 1, between this roller and the drum, is a rod 52, having guide-plates 53 secured thereon and supported thereby. The front ends of these 70 guide-plates are in horizontal alinement and contact with the upper face of the belt 11, and the rear ends of the plates are in position slightly in advance of the roller 50. The outer edges of these plates are curved and provided 75 with curved flanges 54, preferably as shown in Fig. 8. Brackets 55 are fastened to the rod 52, and on each bracket is journaled a disk 56, which is adapted to bear upon the roller 50.

The paper to be ruled is removed from the 80 serving-table 7 and inserted in the pass between the drums 10. It will be carried forward on the belt 11 and will be held in position thereon by the cords 12. The gate 21 will prevent the sheets of paper from passing under the pens 17 85 except at predetermined intervals, and after the sheets have passed thereunder and been properly ruled they will be carried along the belt and between the drum 14 and roller 13 and thence onto the guide-plates 53. As the 90 outer edges of these plates are curved and provided with flanges 54, it will be understood that the side edges of paper will be drawn together and cause the sheet to become concavo-convex or dished, as shown at 57 in Fig. 8. This 95 configuration is produced in order to stiffen the paper sheet longitudinally and permit it to be fed straight forward upon the alining-coil of the stacking device. The roller 50 serves to support the dished sheet during the serving 100 operation, and the flanges 54 not only are employed for stiffening the sheet, but also for directing it accurately between the guide-arms 49. The coil 41 is rotated from the drive-shaft 15 by the gears 28 and 33, shaft 32, gears 34 105 and 35, shaft 36, and gears 44 and 45. The paper is held against rotation with the coil by the guide-arms 49, which serve as resistance means and engage opposite portions of the 110 paper. It will be obvious that the sheets of paper will be carried downward successively by the coil, and when the same reach the lower member of the coil they will be deposited upon the platform 48. The operation of the coil is so timed that one revolution thereof will be 115 produced every time a sheet of paper is fed thereto. Any desired number of spiral members may be employed in the structure of the coil, and as the paper is carried downward thereby the circulation of air produced will 120 dry the ink thereon subsequent to the stacking operation. While the drying and stacking device herein described is preferably formed of one coil, it may, if desired, be constructed of two coils arranged concentric to 125 each other, as illustrated in Figs. 4 and 5. It will be understood that the guide-arms 49 can be adjusted from or toward the coils to accommodate sheets of paper of different sizes, and, if desired, smaller or larger coils can be 130

substituted for the ones employed in connection with the machine. The disks 56 serve to hold the paper firmly upon the guide-plates 53 during its passage thereover.

5 In Figs. 6 and 7 I have shown a modified construction of drying and stacking apparatus which permits the use of different sizes of paper with one coil. By referring to the figures above mentioned it will be seen that the 10 coil 58 is secured at its upper end to a toothed ring 59, having an annular flange 60, which is arranged within and is guided and supported by bearing-plates 61. These bearing-plates are fastened to a cross-strip 62, which 15 serves to support a shaft 63, having a gear 64 thereon for engaging the gear 34 and a gear 65 for engaging the toothed ring 59. Brackets 66 are secured upon the cross-strip 62, and adjustably secured therein are parallel arms 20 67, which are formed integral with parallel vertically-arranged guide-arms 68, which extend downward within the coils, as illustrated. A base-plate 69 is fastened to the platform 48 and has parallel guide-arms 70 thereon, similar to the arms 49 hereinbefore described, and these arms, together with the parallel guide-arms 68, serve to prevent the rotation 25 of sheets of paper fed therebetween and supported by the members of the coil. With 30 this construction it will be seen that sheets of paper the width of which is less than the diameter of the members of the coil can be held in the latter against rotation, and by loosening the arms 67 within their brackets 35 and adjusting them therein the guide-arms 68 can be moved from or toward the guide-arms 70 to accommodate paper of different sizes. It will be seen that the cross-strip 62 of this modified construction is adjustable from or 40 toward the roller 50, and the shaft 63 is supported thereon by standards 71 in substantially the same manner as in the form illustrated by Figs. 1 to 3.

By providing drying and stacking mechanism such as herein described it is unnecessary to employ a drying-belt such as ordinarily used, and the machine is thus rendered extremely compact, and the minimum area of floor-space is required for accommodating it.

50 In the foregoing description I have shown the preferred form of my invention; but I do not limit myself thereto, as I am aware that modifications may be made therein without departing from the spirit or sacrificing any 55 of the advantages thereof, and I therefore reserve the right to make such changes as fairly fall within the scope of my invention.

Having thus fully described the invention, what is claimed as new is—

60 1. In a machine of the class set forth, the combination with feeding and ruling mechanism, of a vertical revoluble coil, and means adjacent to opposite portions of the coil for preventing rotation and lateral displacement of 65 material fed by the coil.

2. In a machine of the class set forth, the combination with feeding and ruling mechanism, of a vertical revoluble coil, and guide-arms adjacent to opposite portions of the coil.

3. In a machine of the class set forth, the 70 combination with feeding and ruling mechanism, of a vertical revoluble coil, guide-arms adjacent to opposite portions thereof, and means for directing material to the coil.

4. In a machine of the class set forth, the 75 combination with feeding and ruling mechanism, of a vertical revoluble coil, guide-arms adjacent to opposite portions thereof, and means for dishing and feeding material to the coil.

5. In a machine of the class set forth, the combination with feeding and ruling mechanism, of a vertical revoluble coil adjustably connected to said mechanism, guide-arms adjacent to opposite portions of the coil, and means 85 for dishing and feeding material to the coil.

6. In a machine of the class set forth, the combination with feeding and ruling mechanism, of a vertical revoluble coil adjustably connected thereto, guide-arms adjacent to opposite portions and in rear of the coil, and means 90 for feeding material to the coil between the arms.

7. In a machine of the class set forth, the combination with feeding and ruling mechanism, of a vertical revoluble coil, adjustable 95 guide-arms adjacent to opposite portions of the coil, and means for directing material to the coil between the guide-arms.

8. In a machine of the class set forth, the 100 combination with feeding and ruling mechanism, of a vertical revoluble coil adjustably connected thereto, parallel guide-arms adjustably mounted adjacent the coil, and means for directing material to the coil between the arms. 105

9. In a machine of the class set forth, the combination with feeding and ruling mechanism, of a revoluble coil arranged in operative relation thereto, parallel guide-arms adjustably mounted adjacent to the coil, and means 110 for directing material to the coil between the arms.

10. In a machine of the class set forth, the combination with feeding and ruling mechanism, of a revoluble coil, and holding means adjacent to opposite portions of the coil for preventing sheets of paper fed to the coil from having loose movement between the members of the latter.

11. In a machine of the class set forth, the 120 combination with feeding and ruling mechanism, of a vertical revoluble coil, mechanism for dishing material and directing it to the coil, and means for preventing rotation and lateral movement of the material in the coil. 125

12. In a machine of the class set forth, the combination with feeding and ruling mechanism, of a vertical revoluble coil, means for preventing the rotation and lateral movement of material within the coil, and stationary ad- 130

justable guide-plates interposed between the feeding mechanism and the coil.

13. In a machine of the class set forth, the combination with feeding and ruling mechanism, of a revoluble coil, guide-arms arranged adjacent to opposite portions thereof, and stationary adjustable guide-plates interposed between the coil and the feeding mechanism.

14. In a machine of the class set forth, the combination with feeding and ruling mechanism, of a revoluble coil, guide-arms arranged adjacent to opposite sides of the coil and parallel therewith, and stationary adjustable guide-plates interposed between the coil and the feeding mechanism and having curved flanges.

15. In a machine of the class set forth, the combination with feeding and ruling mechanism, of a revoluble coil, means for transmitting motion thereto from the feeding mechanism, guide-arms adjustably mounted adjacent to opposite portions of, and parallel with, the coil, and stationary adjustable guide and dishing plates interposed between the coil and the feeding mechanism.

16. In a machine of the class set forth, the combination with feeding and ruling mechanism, of a platform, a revoluble coil supported by said platform, means for transmitting motion from the feeding mechanism to the coil, and guides adjustably mounted on the platform and arranged adjacent to opposite portions of, and parallel with, the coil.

17. In a machine of the class set forth, the combination with feeding and ruling mechanism, of a platform, a revoluble coil having its lower extremity held adjacent to said platform, and guide devices arranged adjacent to opposite portions of the coil.

18. In a machine of the class set forth, the combination with feeding and ruling mechanism, of a platform, a revoluble coil having one end held adjacent to said platform, means for transmitting rotary motion to the coil, plates adjustably mounted on the platform, and guide devices extending from the said plates and arranged near opposite portions of the coil.

19. In a machine of the class set forth, the combination with feeding and ruling mechanism, of a platform, a vertical revoluble coil supported by, and projecting above the platform and having its lower end in stacking relation to the latter, means for transmitting rotary motion to the coil, base-plates adjustably mounted on the platform, and guide-arms extending upwardly from the platform adjacent to opposite portions of the coil, the said guide-arms being movable with respect to each other and the coil.

20. In a machine of the class set forth, the combination with feeding and ruling mechanism, of a revoluble coil, combined guide and dishing devices interposed between the coil and the feeding mechanism, a supporting rotatable element interposed between the coil

and said devices, and means for preventing loose movement and rotation of material fed to the coil while in the latter.

21. In a machine of the class set forth, the combination with feeding mechanism, of a revoluble coil disposed adjacent thereto, combined guiding and dishing devices interposed between the coil and the feeding mechanism, a supporting-roller interposed between the coil and said devices, and means for preventing the rotation of material with the coil.

22. In a machine of the class set forth, the combination with a frame having feeding and ruling mechanism thereon, and a platform, of a revoluble coil supported by the platform, guide-arms adjustably held by the platform adjacent to the coil, guiding and dishing plates interposed between the coil and the feeding mechanism, and a supporting-roller adjacent to said plates.

23. In a machine of the class set forth, the combination with a frame having feeding and ruling mechanism and a platform, of a revoluble coil held by the platform and adjustable in relation to the frame, guide-arms arranged adjacent to the coil and attached to the platform, means for transmitting rotary motion from the feeding mechanism to the coil, guiding and dishing plates interposed between the said mechanism and the coil, and a supporting-roller arranged near the plates.

24. In a machine of the class set forth, the combination with feeding and ruling mechanism and a platform, of a vertically-disposed revoluble coil adjustably mounted in relation to the frame and extending above the platform, guide-arms adjustably secured to the platform and arranged parallel with and adjacent the coil, means for rotating the coil, guiding and dishing plates adjustably interposed between said mechanism and the coil, and a supporting-roller adjacent the plates.

25. In a machine of the class set forth, the combination with feeding and ruling mechanism, of a drying and stacking attachment having a platform, a vertically-arranged revoluble series of coils supported above the platform, guide devices held by the platform and disposed adjacent to, and parallel with, opposite portions of the coils and in rear of the latter, and means for successively supplying material to the coils.

26. In a machine of the class set forth, the combination with feeding and ruling mechanism, of a drying and stacking attachment having a platform, a vertical revoluble coil supported above the platform, and means adjustably mounted on the platform adjacent to opposite portions of the coil for preventing rotation of the paper fed to the latter.

27. In a machine of the class set forth, the combination with ruling and feeding mechanism, of a drying and stacking attachment consisting of a platform, a revoluble vertical series of coils supported thereabove, base-plates

adjustably secured on the platform, vertical guide-arms extending therefrom and parallel with the coils, said arms being arranged adjacent to opposite portions of the coils, and 5 means for successively supplying material to the coils between the arms.

28. In a machine of the class set forth, the combination with feeding and ruling mechanism, of a platform, a vertical revoluble coil 10 thereabove, a toothed ring secured to, and revoluble with, the coil, parallel guide-arms inclosed by the coil, and means for adjustably connecting said arms to the platform.

29. In a machine of the class set forth, the 15 combination with feeding and ruling mechanism, of a vertical revoluble coil, guide-arms parallel thereto, guide-plates interposed between the coil and the feeding mechanism and having curved flanges, and friction-disks journaled above the plates.

30. In a machine of the class set forth, the combination with feeding and ruling mechanism, of a drying and stacking attachment consisting of a revoluble paper-carrying coil, 25 means for conveying the paper to one end of the coil, and guide-arms adjacent to opposite portions and in rear of the coil for preventing lateral displacement or rotary motion of paper fed to the coil.

31. In a machine of the class set forth, the combination with feeding and ruling mechanism, of a revoluble coil, and means adjacent to opposite portions of the coil for preventing lateral displacement in opposite directions and 35 rotation of the material fed to the coil.

32. In a machine of the class set forth, the combination with feeding and ruling mechan-

ism, of a revoluble coil, and means adjustably disposed in relation to opposite portions of the coil for preventing the rotation and lateral 40 displacement of the material fed to the coil and also permitting the latter to operate with material of different sizes.

33. In a machine of the class set forth, the combination with the feeding mechanism 45 thereof, of a revoluble coil arranged adjacent to said feeding mechanism, and means disposed in operative relation to the coil to engage the opposite edges of the material fed to the coil.

34. In a machine of the class set forth, the 50 combination with the feeding mechanism thereof arranged to discharge sheets of paper in horizontal position, of a revoluble coil disposed at an angle to the plane of movement of the said sheets of paper to cause the latter to 55 pass between the members of the coil in a horizontal plane, and means coöperating with opposite portions of the coil to prevent the paper fed thereto from rotating or becoming laterally displaced.

35. In a machine of the class set forth, the combination with ruling and feeding mechanism, of a revoluble coil arranged to receive sheets from the feeding mechanism, and means 60 arranged adjacent to, and exteriorly of, the coil to engage the edges of the sheets and prevent the latter from being thrown outwardly from the coil.

In testimony whereof I affix my signature in presence of two witnesses.

CHARLES A. KEENE.
